UNITED STATES PATENT OFFICE

OTTO EUGENE HUBER, OF READING, PENNSYLVANIA, ASSIGNOR TO THE NARROW FABRIC CO., OF WEST READING, PENNSYLVANIA, A CORPORATION OF PENNSYLVANIA

DESIGN FOR AN ELASTIC NARROW TEXTILE FABRIC

Application filed March 14, 1929. Serial No. 30,469. Term of patent 14 years.

To all whom it may concern:

Be it known that I, OTTO EUGENE HUBER, a citizen of the United States, residing at Reading, in the county of Berks and State of Pennsylvania, have invented a new, original, and ornamental Design for Elastic Narrow Textile Fabric, of which the following is a specification, reference being had to the accompanying drawing, forming part thereof.

The drawing is a plan view of an elastic narrow textile fabric embodying my ornamental design.

I claim:

The ornamental design for an elastic narrow textile fabric, as shown.

In testimony whereof I affix my signature.

OTTO EUGENE HUBER.
